UNITED STATES PATENT OFFICE

120,930

DESIGN FOR A SPARK PLUG CLEANER

Henry L. Hoke and Raymond W. Allen,
Akron, Ohio

Application March 2, 1940, Serial No. 90,645

Term of patent 14 years

To all whom it may concern:

Be it known that we, Henry L. Hoke and Raymond W. Allen, citizens of the United States, residing at Akron, in the county of Summit and State of Ohio, have invented a new, original, and ornamental Design for Spark Plug Cleaner, of which the following is a specification, reference being had to the accompanying drawing, forming part thereof, in which:

Figure 1 is a top plan view of a spark plug cleaner showing our new design;

Figure 2 is a side elevation of the spark plug cleaner shown in Figure 1; and

Figure 3 is a front elevation of the spark plug cleaner shown in Figure 1.

We claim:

The ornamental design for a spark plug cleaner, as shown.

HENRY L. HOKE.
RAYMOND W. ALLEN.
